J. A. H. Sawyer, Attorney.

UNITED STATES PATENT OFFICE.

FREEMAN A. DUNN, OF KEOKUK, IOWA.

VENTILATING ATTACHMENT.

1,223,483.

Specification of Letters Patent. Patented Apr. 24, 1917.

Application filed March 25, 1916. Serial No. 86,721.

To all whom it may concern:

Be it known that I, FREEMAN A. DUNN, a citizen of the United States, residing at Keokuk, in the county of Lee and State of Iowa, have invented certain new and useful Improvements in Ventilating Attachments, of which the following is a specification.

My invention relates to new and useful improvements in combined ventilating attachments and floor warmers, the primary object being the provision of a simple and effective device for warming floors which will, at the same time, cause circulation of air throughout the entire room.

15 A still further object of my invention consists in the provision of a device which will coöperate with any ordinary type of stove, whereby the heat from the stove may be utilized as a means for creating an up

20 current from the floor, with the result that the colder air drawn away from the floor is replaced by warmer air displaced from the upper portion of the room.

In this connection, a still further object 25 of my invention consists in constructing the device in detachable sections connected by coupling collars in order that it may be adjusted to stoves of different styles, and further in order that it may be stored in a relatively small space when not in use; the sections, when separated, being capable of being disposed one within the other to economize in space.

With these and other objects in view, my 35 invention will be more fully described, illustrated in the accompanying drawings, and then specifically pointed out in the claims which are attached to and form a part of this application.

40 In the drawings:

Figure 1 is a side elevation, showing my invention in use;

Fig. 2 is a central vertical sectional view of the device;

45 Fig. 3 is a front elevation of the intermediate section of the device;

Fig. 4 is a transverse sectional view through one of the sections;

50 Fig. 5 is a side elevation, showing the device in knocked down condition for storage or shipment.

Corresponding and like parts are referred to in the following description and indicated in all the views of the drawings by the same reference characters.

Broadly speaking, my invention compre-

hends a tubular body portion open at its ends and adapted to be supported in vertical position with its lower end spaced slightly above the floor and with a portion of its length either engaging or in close proximity to the heated portion of a stove. More specifically, the preferred embodiment of my invention includes a frusto-conical base 10, preferably formed of cast iron or other suitable metal, being provided at its smaller upper end with an upstanding annular flange or collar 11 and at its lower end with peripherally spaced supporting feet 12. Co-operating with this base are a plurality of body sections 13, 14 and 15 and a plurality of connecting rings 16, 17, 18 and 19. Each of these connecting rings is preferably formed of sheet metal and of an internal diameter such that it may be fitted snugly over the upstanding flange 11 of the base. Furthermore, each of the rings, intermediate its height, is formed with an instruck peripheral bead 20.

Each of the body sections 13, 14 and 15 is also preferably formed of suitable sheet metal, such as sheet iron, the metal being bent to form a cylindrical body and having one edge bent outwardly and back upon itself, as shown at 21 in Fig. 4 and then rebent, as shown at 22, to provide a seat 23 for the opposite edge of the strip of metal forming the body member. Because of this construction, one longitudinal edge of a body member may be inserted in the seat 23 formed at the other edge of the body member, whereby the body member will be closed throughout its length or the body member may be expanded to space its opposed edges from each other. The intermediate section 95 of the device, which, in the present instance, is indicated by the numeral 14, is provided intermediate its height and preferably at some point remote from its abutting longitudinal edges with a plurality of openings 24 and at either side of these openings with longitudinally extending slits 25 and in longitudinal alinement with these slits, but below the openings, with additional slits 26. A substantially U-shaped hood 27, of sheet metal, is disposed against the intermediate body member 14 with its intermediate portion extending transversely and inclined downwardly somewhat from the body member 14 and with its side portions abutting against the body portion 14. These side portions are provided with laterally directed

wings 28 formed adjacent their upper and lower ends with U-shaped clefts or slits 29, defining tongues 30 which are indent in such a manner that they may be inserted through 5 the slots 25 and 26 to hold the hood to the intermediate portion 14 in such a manner as to surround the openings 24 therein.

In use, one of the coupling rings or collars is positioned upon the base 10, the lower body section has its abutting edges interlocked, in the manner shown in Fig. 4, and its lower end inserted in the upper end of the collar 16. The instruck bead 20 of the coupling member limits the seating of such 10 member upon the base 10 and also acts as a stop and support for the lower end of the body member 13. A second coupling ring is positioned about the upper end of the body member 13, being held against downward movement over such member by its 15 instruck bead and the intermediate member 14 has its abutting edges interlocked and its lower end seated in the upper end of this second coupling ring. In like manner, a 20 third coupling ring is applied to the upper end of the intermediate body section and receives the lower end of the upper body section, the abutting edges of which are interlocked and held in such position by their 25 coupling ring and by the fourth coupling ring which is secured about the upper end of the upper body section or member. When the device has been so assembled, it is located with its open outer end of the head 27 30 disposed against a heated portion of a stove, indicated by the numeral 31. When so disposed, it will be clear that air entering the lower open portion of the hood will be heated and will pass through the openings 24 of 35 the intermediate section of the body and because of its heat pass upwardly through the body and out at the top in the upper portion of the room. As a result, an upward current of air will be created in the lower portion 40 of the device tending to create a partial vacuum therein so that the cold air in the vicinity of the floor will be drawn up 45 through the base and through the device and discharged at a considerably higher elevation. The discharging of this colder air 50 from the top of the device tends to displace the heated air in the upper portion of the room, while at the same time the withdrawing of cold air from the vicinity of the floor 55 tends to create a vacuum near the floor and, consequently, to draw the heated air in the upper portion of the room downwardly. As will be apparent, this causes a partial circulation of air throughout the entire room, the 60 heated air in the upper portion of the room being drawn downwardly along the floor and the floor thereby warmed.

Obviously, the upper section of the body may be dispensed with, if desired, or the intermediate section may be applied directly

to the lower coupling collar and the lower body section dispensed with, depending upon the type of stove with which the device is employed and upon the elevation at which it is desirable to discharge the air drawn 70 from the lower portion of the room. Obviously, also if the room is exceptionally high, added body sections may be readily applied, together with suitable coupling rings for securing them in place.

When the device is to be shipped or stored, all parts may be separated and then assembled in the manner shown in Fig. 5, in which the coupling rings are seated directly one upon the other, the lowermost being positioned about the upstanding flange of the base and in which the interlocking edges of the body members are separated in order that one body member may be spread somewhat to inclose the vertically alined coupling rings and the other body members correspondingly spread so that each may encircle any body members disposed within it. The hood 27 may then be inserted in the innermost body member, as shown, being 90 readily removable from the intermediate body portion 14 to which it is normally attached.

It will, of course, be apparent that various minor changes in construction may be made 95 without affecting the principle of operation of my device and for this reason I reserve the right to make any changes, within the scope of the appended claims.

Having thus described the invention, what 100 is claimed as new is:

1. A ventilating attachment including a tubular body member adapted to be positioned with its intermediate portion in juxtaposition to the heated portion of a stove, 105 means for supporting the body member in substantially vertical position with its lower end spaced above the floor, and an outwardly projecting hood open at its bottom formed intermediate the length of the body member 110 to engage a stove, the portion of the body member inclosed by the hood being formed with openings.

2. A ventilating attachment including an annular base having supporting feet and an 115 upwardly directed annular flange, a plurality of tubular body members equal in external diameter to the external diameter of the flange, and a plurality of coupling rings equal in internal diameter to the external 120 diameter of the body members and flange and each formed intermediate its length with an inwardly directed stop bead, whereby the coupling rings may connect the body members end to end and one of such body members to the flange, one of the body members being formed in its side with an opening, and a hood open at its lower end carried by 125 such body member and inclosing the opening.

3. A ventilating attachment including an annular base having supporting feet and an upwardly directed annular flange, a plurality of tubular body members equal in external diameter to the external diameter of the flange, and a plurality of coupling rings equal in internal diameter to the external diameter of the body members and flange and each formed intermediate its length with an inwardly directed stop bead, whereby the coupling rings may connect the body members end to end and one of such body members to the flange, one of the body members being formed in its side with an opening, 10 a hood carried by such body member and partially inclosing the opening, and means for detachably connecting the hood to the body member.
4. A ventilating attachment including an annular base having supporting feet and an upwardly directed annular flange, a plurality of tubular body members equal in external diameter to the external diameter of the flange, and a plurality of coupling rings equal in internal diameter to the external diameter of the body members and flange and each formed intermediate its length with an inwardly directed stop bead, whereby the coupling rings may connect the body members end to end and one of such body members to the flange, one of the body members being formed in its side with an opening, 15 and a hood carried by such body member and partially inclosing the opening, said hood being open at its front and bottom, and means for detachably connecting the hood to the body member; said means including 20 struck tongues formed upon the hood and adapted to extend through slots formed in the body member.
- 25

bers to the flange, one of the body members being formed in its side with an opening, and a hood carried by such body member and partially inclosing the opening, said hood being open at its front and bottom.

5. A ventilating attachment including an annular base having supporting feet and an upwardly directed annular flange, a plurality of tubular body members equal in external diameter to the external diameter of the flange, and a plurality of coupling rings equal in internal diameter to the external diameter of the body members and flange and each formed intermediate its length with an inwardly directed stop bead, whereby the coupling rings may connect the body members end to end and one of such body members to the flange, one of the body members being formed in its side with an opening, 40 and a hood carried by such body member and partially inclosing the opening, said hood being open at its front and bottom, and means for detachably connecting the hood to the body member; said means including 45 struck tongues formed upon the hood and adapted to extend through slots formed in the body member.

In testimony whereof I affix my signature.

FREEMAN A. DUNN. [L.S.]
